FRANK DOVE, OF TOPEKA, KANSAS, ASSIGNOR TO A. K. LONGREN, OF KANSAS CITY, MISSOURI.

AEROPLANE STABILIZING MECHANISM.

1,321,094.

Specification of Letters Patent. Patented Nov. 11, 1919.

Application filed February 6, 1918. Serial No. 215,575.

To all whom it may concern:

Be it known that I, FRANK DOVE, a citizen of the United States, residing at Topeka, in the county of Shawnee and State of 5 Kansas, have invented certain new and useful Improvements in Aeroplane Stabilizing Mechanism; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specification.

My invention relates to aeroplane stabilizing mechanism, and more particularly to mechanism for effecting an automatic control of the plane laterals or ailerons to retain the aeroplane equipped with the mechanism in lateral or transverse balance; the principal object of the invention being to provide mechanism of this character controllable by the movement of a pendulum or 25 suspended weighted actuator, and comprising an aerofoil mechanism through which the air current or wind pressure is utilized to move the ailerons to retain the plane in a stabilized position, it being understood 30 that the aerofoil mechanism is quite distinct from any of the usual operating mechanism.

A further object of the invention is to provide mechanism of this character for automatically banking the aeroplane at the necessary angle when a turn is made to insure against side slipping in either direction.

It is also a purpose of my invention to 40 construct a mechanism capable of being attached to a known type of aeroplane.

In accomplishing these objects, I have provided improved details of structure, the preferred forms of which are illustrated in 45 the accompanying drawings, wherein:—

Figure I is a side elevation of a portion of an aeroplane showing a stabilizing device constructed according to the present invention, mounted thereon.

Fig. II is an enlarged side view of the stabilizing mechanism.

Fig. III is a plan view of the same.

Fig. IV is a front view of the mechanism, showing the pendulum for actuating the 55 aerofoil mechanism.

Referring more in detail to the drawings:

1 designates an aeroplane of a type wherein the present mechanism is particularly applicable, and which comprises a body 2, propeller 3, upper and lower planes 4 and 5 60 respectively and a landing carriage 6; the plane 4 being provided at its opposite rearward corners with the hingedly mounted laterals or ailerons 7—8 whereby lateral balance of the plane is maintained. Mounted 65 centrally on the top plane 4 and near its forward edge is an anchor or bearing plate 9 which is fixed to the plane by bolts 10 extending through the plane, and extending upwardly from the said plate is a boss 11 70 wherein the shank 12 of a shaft bearing 13 is pivotally fixed.

Extending through the bearing 13 in such a manner that it may swing pivotally on the plate 9 in a horizontal plane, is a tubular shaft 14, the forward and rearward ends of which terminate respectively a slight distance ahead and back of the corresponding edges of the plane, and fixed to the rearward end of the shaft is a yoke member 15, 75 comprising spaced vertically alining arms 16—16' which at their ends support a vertical pivot pin 17, having its ends projecting slightly beyond the said arms and pivotally supporting an aerofoil 18; the latter being maintained by said pin in a vertical plane and is provided at its forward vertical edge with a recess 19 for receiving the yoke 15 and has vertically alining sockets 20—20' in its upper and lower edges where- 80 in the opposite ends of the pin 17 are pivotally seated to retain the aerofoil in operative position.

Extending through and revoluble within the shaft 14 and having its opposite ends 95 projecting slightly therefrom, is a rod 21, and fixed to the forward end of said rod is a swinging weighted actuator comprising a rod 22 having a weight 23 adjustably mounted thereon which maintains the rod 22 in 100 vertical alinement. The rod 22 also comprises a vertical standard 24' that continues above the pivot point whereon an aerofoil 25 is mounted and adapted to pivot in a vertical plane. The function of this aerofoil 25 105 is only to steady the actuator and parts connected therewith, and to prevent any swinging tendency of the actuator which would cause an uncertain travel of the plane.

At the rearward end of the rod 21 I affix 110

an outwardly and upwardly curved lever arm 26 which at its upper end is pivotally connected by a link 27 to the aerofoil at the upper side of the recess. With this connection, swinging of the actuator toward either end of the plane will revolve the rod 21 to move the rear end of the aerofoil 18 in a like direction.

Attached to the shaft 14 by means of a pin 28 extending therethrough at a short distance ahead of the bearing 11 is a plate 29 and fixed to its opposite ends and extending to the brackets 32 and 32' on the laterals of the plane are cables 30-30' which 10 operate over sheave wheels 31-31' mounted adjacent the ends of the plane, there being similar brackets and connecting cables below the plane, as best shown in Figs. I, II and III.

With the stabilizing device so constructed and mounted, and the cables 30-30' attached to the ailerons, while the plane maintains a lateral balance the rudders follow and are supported in alinement with the 25 direction of travel, but should one end of the plane drop or be forced down for any reason, the weighted actuator will swing toward the lower end of the plane. This movement of the weighted actuator revolves 30 the rod 21 and the latter through the arm and link connection moves the rearward edge of the aerofoil 18 toward the lower end of the plane and presents that side of the aerofoil to the wind pressure; this causes 35 the aerofoil to move the rearward end of the shaft 14 toward the higher end of the plane until the aerofoil is brought into alinement with the direction of travel. The movement of the shaft 14 by the connection 40 of the cables 30-30' moves the aileron at the higher side of the plane upwardly and lowers the opposite aileron so that the plane is forced back to normal position, whereupon the weighted actuator moves the aerofoil 45 18 back into alinement with the shaft 14 and the same follows in alinement with the direction of travel of the plane.

It is also seen that should it be desired to turn the aeroplane, the necessary banking 50 will be automatically accomplished. This is due to the fact that when a turn is started, centrifugal force on the weighted actuator will swing the weight toward the outer side of the curve a certain distance in 55 accordance with the rate of travel and degree of the turn being made. As the weighted actuator swings outward, as before described, the ailerons are actuated to raise the aeroplane at the outer side of the turn 60 so that it will be banked precisely at the right incline to make the turn without any side slipping.

In order that the automatic feature may be disconnected and the ailerons be manually operated, I attach a cable 33 to the pin

28 which extends to a position accessible to the aviator, so that if an occasion is necessary, he may disconnect the parts by pulling the pin from the shaft 14 which would allow the aerofoil mechanism to operate 70 idly without effect on the stabilizing ailerons.

It is apparent that with the parts so constructed and mounted, the plane will be maintained automatically in a lateral or 75 transverse stabilized position, and side slipping due to loss of control of the mechanism, or by improper banking at turns, is prevented.

Having thus described my invention, what 80 I claim as new therein, and desire to secure by Letters-Patent, is:

1. A stabilizer for aeroplanes comprising a swingingly supported weighted actuator, a laterally swinging member connected to the weighted actuator, an aerofoil carried by the laterally swinging member, means connecting the aerofoil and the actuator whereby movement of the actuator will impart movement to the aerofoil, and means connected to the laterally swinging member for actuating the ailerons of an aeroplane. 85

2. A stabilizer comprising a laterally swinging member, a weighted actuator swingingly mounted upon one end of the 90 laterally swinging member, an aerofoil swingingly secured to the other end of the laterally swinging member, operative connections between the laterally swinging actuator and the aerofoil, and means carried 95 by the laterally swinging member for connection to the ailerons of an aeroplane.

3. A stabilizer comprising a laterally swinging member, a weighted actuator swingingly mounted upon one end of the 100 laterally swinging member, an aerofoil swingingly secured to the other end of the laterally swinging member, operative connections between the laterally swinging actuator and the aerofoil, and cables carried 105 by the laterally swinging member for connection to the ailerons of an aeroplane. 110

4. In combination with an aeroplane comprising a plane having ailerons at its opposite ends for maintaining its lateral stability, a stabilizing device comprising a supporting shaft, an aerofoil mounted at one end of the shaft for controlling the movement thereof, a swinging weighted actuator at the opposite end of the shaft operatively 115 connected with the aerofoil to effect its movement on horizontal displacement of the plane, and means for operating the ailerons by movement of the supporting shaft 120 to move the plane to a stable position. 125

5. In combination with an aeroplane comprising a plane having ailerons at its opposite ends for maintaining its lateral stability, a stabilizing device comprising a horizontal, pivotally mounted supporting shaft, 130

an aerofoil pivotally mounted at one end of the said shaft, a swinging weighted actuator at the opposite end of the shaft operatively connected with the aerofoil to move the latter

5 on movement of the plane from a stable position to actuate the supporting shaft about its pivotal mounting, and means operatively connecting the supporting shaft with the ailerons for actuating the latter to move 10 the plane to a stable position.

6. In combination with an aeroplane comprising a plane having ailerons at its opposite ends for maintaining its lateral stability, a stabilizing device comprising a horizontally disposed supporting shaft pivotally mounted on said plane, an aerofoil pivotally mounted at the rearward end of said shaft, a swinging weighted actuator mounted at the opposite end of the shaft and operatively 15 connected with the aerofoil, so that movement of the actuator toward either end of the plane operates the aerofoil to move the rearward end of the supporting shaft in the opposite direction, and cables attached to 20 the forward end of the supporting shaft and to the ailerons for actuating the same to move the plane to stable position.

7. In combination with an aeroplane comprising a plane having ailerons at its opposite ends for maintaining its lateral stability, a stabilizing device comprising a horizontally disposed supporting shaft pivotally mounted on said plane, an aerofoil pivotally mounted at the rearward end of said shaft, 35 a rod extending longitudinally and revolvably through the supporting shaft, a swinging weighted actuator fixed to the forward end of said rod, a lever arm mounted on the opposite end of said rod and operatively connected to said aerofoil in such a manner that movement of the actuator toward either end of the plane actuates the aerofoil to move the rearward end of the shaft in an opposite direction, and cables attached to 40 the forward end of the supporting shaft and to the ailerons for actuating the same to move the plane to stable position.

8. In combination with an aeroplane comprising a plane having ailerons at its opposite ends for maintaining its lateral stability,

a stabilizing device comprising a horizontally disposed tubular shaft, pivotally mounted adjacent its forward end on said plane, an aerofoil pivotally mounted at the rearward end of said shaft to normally retain the shaft in alignment with the direction of travel of the plane, a rod revolvably mounted in the tubular shaft and extending from the opposite ends thereof, a swinging weighted actuator fixed to the forward end 55 of said rod, a lever arm fixed to the opposite end of said rod and a link pivotally connecting said arm with said aerofoil, whereby revolvable movement of the rod under the influence of the actuator moving toward either end of the plane will actuate the aerofoil to move the forward end of the shaft in a like direction, and cables attached to the forward end of the shaft and to the opposite end ailerons whereby the latter may 60 be actuated to move the plane to stable position.

9. The combination with an aeroplane comprising a plane having ailerons at its opposite ends for maintaining its transverse balance, a stabilizing device comprising a tubular supporting shaft pivotally mounted centrally on said plane, and adapted to move on its pivot in a horizontal plane, an aerofoil pivotally supported at the rearward 75 end of the shaft in a vertical plane and adapted to retain the supporting shaft normally in alignment with the direction of travel of the plane, a rod revolvably mounted in the tubular shaft and extending from its 80 opposite ends, a swinging weighted actuator fixed to the forward end of said rod, a lever arm fixed to the opposite end of said rod, a link connecting the arm with the aerofoil so that movement of the actuator toward 85 either end of the plane will actuate the aerofoil to move the forward end of the supporting shaft in a like direction, cables fixed to the forward end of the shaft and to the said ailerons to actuate the latter to 90 retain the plane in transverse balance, and a stabilizing aerofoil mounted freely on the pendulum for the purpose set forth.

In testimony whereof I affix my signature.
FRANK DOVE.
